[57] ABSTRACT

A digital display device includes an upper and lower row of electroluminescent display elements each controlled by a silicon controlled rectifier gated by the output of a stage of a data buffer for applying an alternating potential to each display element; a blanking control circuit for controlling the amplitude of the alternating potential applied to the display elements; an image control switch for selectively operating the display device to be unblanked, to be blanked or to be automatically blanked except when input lines are energized; and a display time extension circuit for allowing a display device to be operational for a period of time after the input lines are de-energized.

FIG. 4

PULSE ANALYZING TESTER

This is a division of application, Ser. No. 88,298, filed Nov. 11, 1970.

BACKGROUND OF THE INVENTION

This invention relates to display devices and more particularly to digital display devices having a number of discrete display elements and including driving circuits to activate each individual display element according to the input to each driving circuit.

In the past, digital display devices have most commonly consisted of a number of individual lamp elements such as incandescent bulbs each for indicating the presence or absence of a particular bit in a data stream.

The prior art control circuitry does not permit selectively blanked, unblanked or automatically blanked image display. Also, the prior art does not provide a bright flicker-free data display.

SUMMARY OF THE INVENTION

Therefore, a digital display device according to the present invention includes a plurality of display elements arranged in rows wherein each element is activated by a gated power control device. Data is transferred from a data buffer to the gate of the power control devices to blank or unblank the respective display element. Control logic for controlling the application of the power source to the gated power control devices permits the display to be selectively blanked, unblanked, or automatically blanked except when data input lines are active.

The control logic also extends the time for a display device to be active for a duration after the data input has been deactivated to enable a brighter more flicker-free display. The display device includes an upper row of illuminable indicators and a lower row of illuminable indicators. The illuminable indicators may be neon indicator lamps, electroluminescent elements, light emitting diodes, and the like. The display device selectively may be operated (1) to be blanked at all times, (2) to be unblanked at all times, or (3) to be automatically unblanked when incoming signals are presented and automatically blanked in the absence of incoming signals. Visual indicators are provided to indicate to an operator the status of the basic control devices.

It is a feature of this invention to provide a test instrument with a digital display device which may be blanked at all times, unblanked at all times, or automatically unblanked in response to an incoming signal and automatically blanked in the absence of an incoming signal.

It is a feature of this invention to provide for the display of an incoming signal in both rows of a digital display device which has two rows or to provide for the display of two simultaneously incoming signals in the

two rows of a digital display with one signal displayed in one row and the other signal displayed in the other row.

The foregoing and other objects, features and advantages of the invention will be apparent from the following more particular description of a preferred embodiment of the invention, as illustrated in the accompanying drawings.

BRIEF DESCRIPTION OF THE DRAWINGS

FIG. 1 illustrates in block form a test instrument employing to this invention.

FIGS. 2A and 2B show a digital display device according to the present invention.

FIG. 3 shows a section view of the digital display device of FIGS. 2A and 2B.

FIG. 4 is a schematic diagram showing image control logic to support the digital display device shown in FIGS. 2A and 2B.

DESCRIPTION OF THE PREFERRED EMBODIMENTS

This specification and description of the instant invention is compiled from a more complete description of a system embodying the present invention which appears in copending application, Ser. No. 88,298, filed Nov. 11, 1970.

Reference is made to FIG. 1 which illustrates in block form the general system of a test instrument employing to this invention. A device under test 10 supplies signals to amplitude discriminators 12 through 15. Signals from the amplitude discriminators 12 through 15 are supplied through gating and control circuits 20 to an upper buffer 22 and a lower buffer 24. Alternatively, signals from the amplitude discriminators 12 through 15 may be supplied through the gating and control circuits 20 to the lower buffer 24 only. A ring circuit 26 operates successively stages of the upper buffer 22 and the lower buffer 24 to sample and store signals from the amplitude discriminators 12 through 15. The ring circuit 26 is operated by an oscillator 28. The oscillator 28 is turned on and off in response to control signals from the gating and control circuits 20. A display device 40 has an upper row 42 of electroluminescent elements and a lower row 44 of electroluminescent elements. Information stored in the upper buffer 22 may be displayed by the upper row 42 of electroluminescent elements, and information stored in the lower buffer 24 may be displayed in the lower row of 44 of electroluminescent elements.

An image control switch 190 in FIG. 4 has a three position lever, and various ones of the contacts 1 through 20 are grounded by operating the lever. Contact 4 is grounded as shown. By a jumper arrangement grounded contact is connected to contacts 6, 7, 9, 10, 15, and 19. Table 1 below shows which ones of the contacts are grounded for the various positions of the switch lever.

TABLE 1

Lever position	Contact numbers																			
	1	2	3	4	5	6	7	8	9	10	11	12	13	14	15	16	17	18	19	20
Up-----	X	X	X	X	X	X	X	X	X	X					X			X	X	
Center----	X	X	X	X	X	X	X	X	X	X				X		X		X	X	
Down-----X		X	X	X	X	X	X	X	X	X				X		X		X	X	

Contact 1 of the switch 190 is connected to an And circuit 191, and contact 5 is connected to an Or circuit 192. The Or circuit 192 is connected to the And circuit 191. Output signals from the And circuit 191 on a line 193 are used to control the blanking and unblanking of the display device of 40 in FIG. 1. The image control switch 190 is a three position lever switch, and the three positions control the blanking, unblanking, and clearing of the display device 40 in FIG. 1. When the switch lever is up, the display 40 in FIG. 1 is unblanked. When the image control switch 190 in FIG. 4 is operated with its switch lever centered, it automatically clears the display device 40 in FIG. 1. When the image control switch 190 in FIG. 4 is operated with its switch lever down, it blanks the display device 40 in FIG. 1.

An Or circuit 194 in FIG. 4 is connected to an indicator lamp 195. A single shot 196 has its output connected to the Or circuits 192 and 194. Signals on the line 163 in are supplied through an inverter 197 to the Or circuit 194. The signals on a line 200 are supplied to the Or circuits 192 and 194. The Or circuit 194 responds to a negative signal on any of its input lines and provides a negative output signal, as indicated by the half arrowhead on the output line at the junction with this Or circuit, which is effective to illuminate the lamp 195. The lamp 195 is illuminated whenever the ring circuit 26 in FIG. 1 is operated. The Or circuit 192 responds to a negative signal on any one of its input lines, as indicated by the half arrowhead at the junctions of these lines with this Or circuit, and supplies a positive output signal to the upper input of the And circuit 191.

Reference is made next to FIGS. 2A and 2B for a detailed illustration of the display element 40. The display element 40 has an upper display register 42 and a lower display register 44. The upper display register 42 is composed of a plurality of phosphor segments 1101 through 1105. There are as many phosphor segments in each display register as there are stages in the upper and lower buffers. However, only five phosphor segments are shown, and they represent stages 1, 2, 3, 19 and 20. Phosphor segments 1101 through 1105 display information in the respective stages 1, 2, 3, 19, and 20 of the upper buffer. Phosphor elements for stages 4 through 18 of the upper buffer are not shown in the interest of simplicity. The lower register 44 of the display device 40 includes phosphor elements 1111 through 1115 which display information stored in respective stages 1 through 3, 19, and 20 of the lower buffer 24. Phosphor elements for stages 4 through 18 of the lower buffer 24 are not shown in the interest of simplicity.

Signals from the upper buffer 22 on the lines 801 through 805 are supplied to respective silicon controlled rectifiers 1121 through 1125. The silicon controlled rectifiers 1121 through 1125 are connected to respective phosphor elements 1101 through 1105. Signals from the lower buffer 24 on lines 901 through 905 are supplied to respective silicon controlled rectifiers 1131 through 1135 which in turn are connected to corresponding phosphor elements 1111 through 1115. A source of alternating current 1141 in FIG. 2B supplies an alternating potential on a line 1143 to the silicon controlled rectifiers 1121 through 1125 and 1131 through 1135. A blank control 1142 responds to signals on the line 193 to control the alternating source 1141. A positive signal on the line 193 operates the blank control 1142 to reduce the amplitude of the source 1141 thereby to deactivate the silicon controlled rectifiers 1121 through 1125 and 1131 through 1135. A negative signal on the line 193 operates the blank con-

trol 1142 to increase the amplitude of the source 1141 thereby to condition the silicon controlled rectifiers 1121 through 1125 and 1131 through 1135, and the silicon controlled rectifiers may then respond to signals from the upper and lower buffers. When the source 1141 is applied to the line 1143, the silicon controlled rectifiers 1121 through 1125 respond to positive signals on corresponding lines 801 through 805 to illuminate associated phosphor elements 1101 through 1105. When the source 1141 is applied on the line 1143 to the silicon controlled rectifiers 1131 through 1135, they respond to positive signals on respective lines 901 through 905 to illuminate corresponding phosphor elements 1111 through 1115. When the source 1141 is removed or its amplitude is decreased sufficiently, the silicon controlled rectifiers 1121 through 1125 and 1131 through 1135 are deactivated, and the associated phosphor elements 1101 through 1105 and 1111 through 1115 are not illuminated by positive signals on the associated lines 801 through 805 or the lines 901 through 905.

Reference is made next to FIG. 3 which is a view taken on the line 25A—25A in FIG. 2A showing phosphor elements 1101 and 1111 in cross section, and associated circuit components are shown connected therewith. The silicon controlled rectifiers 1121 and 1131 are connected through respective connecting pins 1150 and 1151 to associated phosphorous elements or segments 1101 and 1111. These phosphorous segments are attached to a transparent electrode 1152. The transparent electrode 1152 is protected by a glass plate 1153. The source of alternating current 1141 is connected between the transparent electrode 1152 and the silicon controlled rectifiers 1121 and 1131. The blank control 1142 in FIG. 2B is a silicon controlled rectifier 1149 and resistors 1154 and 1155 which form a series circuit. The resistor 1154 is variable. The alternating current source 1141 is shunted by the series circuit including the silicon controlled rectifier 1149 and the resistors 1154 and 1155. When a positive signal is supplied on the line 193 to the silicon controlled rectifier 1149, this rectifier is turned on, and most of the power from the source 1141 is dissipated in the resistors 1154 and 1155. This causes the silicon controlled rectifiers 1121 and 1131 to be deconditioned or turned off whereby the display 40 is blanked. When a negative signal is supplied on the line 193 to the silicon controlled rectifier 1149, this rectifier is deconditioned or turned off, and the power from the source 1141 is applied to condition the silicon controlled rectifiers 1121 and 1131. If a positive signal is applied on the line 801 to the silicon controlled rectifier 1121, it then conducts, and the signal from the source 1141 is supplied through the pin 1150 to the phosphor segment 1101. The signal across this phosphor segment causes it to be illuminated, and light is projected outwardly from the face plate 1153. If a positive signal is applied on the line 901, the silicon controlled rectifier 1131 is rendered conductive, and the signal from the source 1141 is applied across the phosphor segment 1111. This causes the phosphor segment 1111 to be illuminated and light is projected from the face plate 1153. Thus it is seen how the display device 40 in FIGS. 2A and 2B is operated in some instances where it is not essential for an operator to view the display device 40, a positive signal may be applied on the line 193 to blank the display. This increases the useful life of the phosphorous segments.

The image control switch 190 in FIG. 4 permits an operator to control the display 40 in FIGS. 2A and 2B.

When the image control switch 190 is set to the stored (normal) position, the signals being displayed are retained until replaced by signals in the next sweep. the ring circuit is not. With the image control switch 190 in FIG. 4 set to the auto cleared position, the display is retained long enough to be seen and then is cleared. This is useful during trouble analysis to prevent confusion as to whether a display is the result of one specific trial or is left over from a previous trial. When the image control switch 190 is set to the blanked position, no display is seen, but all other functions are carried out by the test instrument in FIG. 1.

Since an oscilloscope and the test instrument in FIG. 1 display signals for analysis, a comparison of the two types of devices is appropriate. The oscilloscope creates a visible display with an electron gun which directs a stream of electrons against the inner face of a cathode ray tube. This inner face is coated with a material which glows under such bombardment and persists in glowing for a short time after the bombardment ceases. The point where the electrons strike the face of the cathode ray tube may be shifted in both the horizontal and vertical planes by impressing voltages on the horizontal and vertical deflection plates between the electrons flow. The horizontal plates are generally connected to a variable oscillator which causes the electron stream to sweep across the face of the cathode ray tube at a known rate and then quickly fly back to begin another such sweep. The vertical deflection plates generally are connected to a signal source which causes the stream of electrons to shift vertically in proportion to the input signal voltage as the horizontal sweep takes place. This results in a displayed line the shape of which represents the signal during a known period of time. The device according to this invention does not utilize a cathode ray tube, electron gun, or deflection plates. It does, however, have a display face containing an upper and lower row of segments or phosphor elements as shown in FIG. 1. There are 20 such elements in each row, and each element represents a distinct time interval of the input signal. These elements are able to glow because of electroluminescence which is a property of emitting light when an alternating current signal is applied. Very little heat is emitted by electroluminescence. The light produced is roughly proportional to the voltage and frequency of the excitation current. The excitation source may be one which provides an alternating signal of 290 volts with a frequency of 400 cycles per second.

The device in FIG. 1 displays information in digital or binary form using the two rows of phosphor elements in contrast to the analogue display presented by an oscilloscope. The device in FIG. 1 takes successive samples of an input signal over a given time period, and the signal during each time increment is sampled to determine whether or not it exceeds the clipping level of the associated amplitude discriminator. If the input signal during a given time increment exceeds the clipping level, the associated phosphor element is illuminated. Otherwise, the associated phosphor element remains dark. This sampling action is different from the horizontal sweep of an oscilloscope even though both devices generate a display. The device in FIG. 1 has a variable sweep range, and the sweep may vary from 1.25 seconds per time increment to 50 nanoseconds per time increment. The negative signal on the line 200 is supplied also to the Or circuit 192 which in turn provides a positive output signal to the And circuit 191. Since the image control switch 190 is set to the stored

position, contact 1 is open, and this conditions the lower input of the And circuit 191. Consequently, the And circuit 191 responds to positive signals on its input lines and supplies a negative output signal on the line 193 which operates the blank control 1142 in FIG. 2B to unblank the display 40 whereby signals stored in the upper and lower buffers may be visually displayed. It is pointed out that the image control switch 190 provides a constant ground level from contact 5 whenever this switch is placed in the stored position. Consequently, the ground potential is effective to operate the Or circuit 192 to provide a positive output signal as long as this switch remains in the stored position. This makes it unnecessary to utilize the negative output signal on the line 200 in this instance, but the negative signal on the line 200 is effective to unblank the display whenever the image control switch 190 is in the auto cleared position. The negative signal on the line 200 is supplied also to the Or circuit 194 in FIG. 4 which in turn supplies a negative signal from its output to the triggered lamp 195 thereby to illuminate this lamp. Assume that the switch 190 in FIG. 4 is in the auto cleared position. When a sweep is initiated as reflected by the turning on of the ring start latch in the line 200 from the reset output of latch is presented to the lower leg of Or circuit 192. The output of 192 is plus which is presented to And circuit 191. The output of And 191 changes to a minus condition which unblanks display 40 as previously explained. For the same reasons previously described, a very short duration sweep, results in a very short time during which display 40 is unblanked. This time could be extremely short and prevent operator observation of patterns occurring during the sweep. Referring now to single shot 196 shown in FIG. 4 it can be seen that the output of single shot 196 is connected to the input of Or circuit 192. The center leg of Or circuit 192 thus is changed to a minus condition at the completion of the sweep for the duration of single shot 196. This drives the output of Or circuit 192 into its plus state which conditions the upper leg of And circuit 191. Thus, line 193 is in a minus condition for 120 milliseconds following the completion of the sweep. For the foregoing examples it was assumed that the lower leg of And circuit 191 is in the plus conditioned state. It has been previously shown that contact 1 of the image control switch 190 is in the plus state when the switch is in the auto cleared position. In review, the function of the single shot 196 primarily is to extend the duty cycle of display 40. This assures visual observation by an operator under all conditions. The worst case is that of fast sweep speeds occurring only once or at a very low repetition rate.

While the invention has been particularly shown and described with reference to a preferred embodiment thereof, it will be understood by those skilled in the art that the foregoing and other changes in form and details may be made therein without departing from the spirit and scope of the invention.

What is claimed is:

1. A digital display device having an upper row of display elements and a lower row of display elements, a plurality of input lines for supplying signals to be displayed, a plurality of individual switch elements, said plurality of input lines being connected to said plurality of individual switch elements, said plurality of individual switch elements being connected into the individual display elements of the upper and lower rows of display elements,

a source of alternating current potential, first control means connected to said source of alternating potential for controlling the magnitude of the alternating current potential source applied to said display device, said source of alternating current potential being supplied to said individual switch elements, each individual switch element responding to the alternating current signal and a signal on its input line to illuminate the associated display element, and

second control means, connected to said first control means, for selectively operating said display device to be unblanked at all times, to be blanked at all

times, or to be automatically blanked at all times except when said input lines are energized.

2. The device of claim 1 further comprising third control means for extending the time of operation of the display device whenever the input lines are de-energized and the display is to be automatically blanked.

5 3. A digital display device according to claim 1 wherein each of said plurality of individual switch elements comprises a gated rectifier; and
10 wherein each of said display elements comprises an electroluminescent phosphorus element.
